CLAIM

The ornamental design for optical headwear for augmented reality, as shown and described.

DESCRIPTION

FIG. 1 is a front view of optical headwear for augmented reality according to the present design;

FIG. 2 is a front perspective view thereof;

FIG. 3 is a top plan view thereof; and,

FIG. 4 is a left side view thereof.

Broken lines in the drawings are for the purpose of illustrating environmental structure and form no part of the claimed design.
